Inventor:
Joseph Harrison Jr.

UNITED STATES PATENT OFFICE.

JOSEPH HARRISON, JR., OF PHILADELPHIA, PENNSYLVANIA.

IMPROVED DEVICE FOR REMOVING INCRUSTATIONS FROM STEAM-BOILERS.

Specification forming part of Letters Patent No. 35,678, dated June 24, 1862.

To all whom it may concern:

Be it known that I, JOSEPH HARRISON, Jr., of the city of Philadelphia, in the State of Pennsylvania, now residing temporarily in the city of Paris, in the Empire of France, have invented a new and useful Improvement in the Mode of Removing Scale, Sediment, and other Deposits from the interior of Steam Boilers, and especially from those constructed upon the plan for which Letters Patent of the United States were issued to me on the 4th day of October, in the year 1859; and I do hereby declare that the following is a true and exact description of my said improvement, which will be better understood by reference to the drawing accompanying this specification as a part hereof.

The drawing; Figure 1, shows in section one of the units of my improved boiler.

I take out the bolt used in holding the units together, as described in the specification of my aforesaid Letters Patent, at any point where the boiler needs cleaning, and introduce into the neck of the units a wrought iron or other metal tube, as shown in section in the drawing. At a short distance from the end of the tube I cut a slot transversely through it. In this slot I place a piece of steel or iron, *a*, about one inch thick and as wide as the outside diameter of the tube. From a center midway between the ends and edges of this piece of steel I bore a hole, *b*, and from the center of this hole I strike a circle, fixing the length of the piece, which is about one inch smaller than the largest inside diameter of the unit, the slot in the tube being made more than one inch larger than the steel plate. Through the hole in the plate, and through corresponding holes in the tube, a steel pin is put, finishing even at the ends with the outside of the tube. The plate *a* turns freely on the pin to any point needed. Inside the tube, which is enlarged at that point for the purpose, I place small connecting-links *c*, which pass on each side of the plate *a*, to the point *d*, where another hole is bored in the plate *a*. Through this hole and through corresponding holes in the links I put another steel pin, connecting the plate and links together, for the purpose hereinafter to be described. At the ends of the steel plate, in a mortise or mortises, I place the cutters *e e*—one or more on each end. The tube described may be of any length to suit the number of units to be cleaned, and if very long may be made in sections, for greater

facility of handling. The operation of the above arrangement is as follows:

When the boiler is opened at any part for cleaning, the necks of the units are first cleaned of deposit, so that the tube may pass through them. When the tube is in the unit, by drawing on the links *c*, at the point *f*, in the direction of the arrow, the plate *a* turns upon its center *b*, causing the steel cutters to come in contact with the deposit on the inside of the unit at *g g*. Now, if the tube is turned from the end outside, either by hand or other power, the cutters turning slowly on the center *b*, at the same time the interior of the unit will be cleaned of deposit with great certainty and facility, no matter how hard the deposit may be.

In removing the deposit, as above described, I prefer to commence at the far ends of the row of units, if they are horizontal, or nearly so, and as fast as any one unit is cleaned of the deposit on its inside surface, so as to remove the powdered matter, I follow it up with a pipe nearly the same size as the neck of the unit, this pipe having a flexible end which dips down to the bottom of the unit. By the application of a wind-fan or other means at the outside end of the pipe the powdered matter is drawn out. If it should happen that it would be better to cut out the deposit with the units filled or partly filled with water, the powdered matter can be drawn out with the water by a pump. When the units are vertical, the powdered matter falls of itself when the lower caps are off.

The rod *B* may be used in combination with a rod in place of a tube, and the cutters may be dispensed with and the extremities of the bar *a* be fashioned so as to act in cutting away the scale or sediment to be removed. These modifications of form do not affect the principle of my invention.

What I claim as new, and desire to secure by Letters Patent, is—

The combination of the tube *A* with the rod *B* and the bar *a*, and the cutters *E* and *E*, whereby the cutters, which are to operate inside of a steam-chamber, may be introduced through an opening of a smaller diameter than that of the chamber itself.

In testimony whereof I have signed my name to this specification in the presence of two subscribing witnesses.
